UNITED STATES PATENT OFFICE.

EPHRAIM C. SOOY, OF KANSAS CITY, MISSOURI.

BALING-PRESS.

SPECIFICATION forming part of Letters Patent No. 627,812, dated June 27, 1899.

Application filed September 29, 1898. Serial No. 692,243. (No model.)

To all whom it may concern:

Be it known that I, EPHRAIM C. SOOY, a citizen of the United States, residing at Kansas City, in the county of Jackson and State of Missouri, have invented a certain new and useful Improvement in Baling-Presses; and I do hereby declare that the following is a full, clear, and exact description of the invention, such as will enable others to make and use the same, reference being had to the accompanying drawings, forming a part of this specification.

The invention has for its object, primarily, the means for feeding automatically the loose material to be baled within the feed-chamber of the press anterior to the compression by the head-block; second, the initial compression of the loose material to be baled within the hopper, and, third, to retain the given position of the division-boards on being inserted within the feed-chamber of the press.

My invention consists in the novel construction and combination of parts, such as will be first fully described, and specifically pointed out in the claims.

In the drawings, Figure 1 is a side elevation in detail of the feed and baling chamber of a horizontal baling-press, showing a broken portion of the bed-plate of the press and of the pitman operating the head-block, and the hopper and the novel feeder on the baling-chamber in a raised position and the power-transmitting devices extending to the pitman. Fig. 2 is a vertical sectional view of the portions of the baling-press as seen in Fig. 1, showing also the position of the feeding devices at the limit of rebound of the head-block and pitman in dotted lines, also showing the guides and rest upon the vibrating end of the hopper for the division-board. Fig. 3 is a vertical sectional view taken upon the line xx of Fig. 1 and showing the winged feeder within the feed-chamber of the press. Fig. 4 is a detail view in perspective of the novel rebounding feeder, showing the hinged spring-actuated wings and a broken portion of the vibrating bar. Fig. 5 is a broken detail view in perspective of the hopper and feed-receptacle, showing the movable end of the hopper, the head-block, and a portion of the pitman and the rope operating the feeder connected with the pitman. Fig. 6 is a view in

perspective of the division-board. Fig. 7 is a horizontal sectional view of the hopper, taken upon the line yy of Fig. 1. 55

Similar letters of reference indicate corresponding parts in all the figures.

In the drawings, to which reference is made, A represents the feed-receptacle of an ordinary horse-power baling-press for the baling of the material in the field, and B is the baling-chamber, connected with the feed-chamber and in the same horizontal plane.

C C are the traction-wheels supporting the feed-receptacle and baling-chamber. 65

D is the bed-plate, connected with the bottom of the feed-receptacle, and which also supports the power in this class of baling-presses.

E is the reciprocating head-block in the feed-chamber, and F is the pitman operating the head-block.

In illustration of my invention I have shown a portion only of the pitman, it being obvious that any power in common use may be applied to the pitman for reciprocating the head-block and compressing the material within the feed-receptacle. 75

G represents the hopper for the reception of the loose material to be baled, and $g g$ are sides to said hopper, which incline outwardly at an angle to the side of the feed-receptacle. The lower edge portion of each side g extends below the upper edge of the feed-receptacle, and upon the outer side portion of said receptacle and at a point equidistant from the opposite ends of each side the said lower portion is separated at g^0 , the rear end portion of said edge being secured to the feed-receptacle by the links $g^2 g^2$. The forward end 90 portion of the lower edge of each side is bent outwardly from the outer side of the feed-receptacle, so as to leave a passage g^* for the vibrating bar, hereinafter described. (See Fig. 7.) 95

g^3 is the rear end of the hopper, which inclines rearwardly at an angle to a vertical line drawn through the feed-receptacle and is secured fixedly to the sides $g g$ of the hopper. In the end g^3 is a vertical slot g^X , which is flared at the upper portion of said end g^3 .

g^4 is the forward movable end of the hopper. Upon the outer side of the end g^4 are separate vertical flanges $g^5 g^5$. With each

one of said flanges g^5 is connected by bolts the upper end of an upright vibrating bar g^7 . The lower end of said bar extends through the passage g^8 between the outer side of the feed-receptacle and the lower edge of the side g of the hopper G , and is connected with the outer side portion of the base-plate D of the press at a point nearly equidistant from the line of the respective ends of the feed-receptacle A . Upon the forward end and inner side portion of each side g is an inclined bar g^9 , against which the movable end g^4 of the hopper rests in an inclined position. With the inner side portion of each flange g^5 , near its upper end, is connected a guide-bar g^9 , which extends outwardly and at right angles to the end g^4 . A short distance upwardly from the lower edge of the end g^4 is an angle-bar g^{10} , which is arranged horizontally in position on the outside portion of said end and forms a step for the division-board. A short distance above the step g^{10} is a horizontal block g^{12} , connected with the end g^4 . Between the respective flanges g^5 g^5 on the outer side of the receptacle A are spring guide-plates g^{14} , which retard the bars g^7 and the end g^4 .

With the rear end and upper side portion of the head-block E is connected by the hinge e a folding plate H . Upon the upper side of the plate H is bolted, a short distance from the hinge e , an angle-plate h , which forms a carrier for the movable end g^4 of the hopper, a portion of which angle-plate extends at right angles to the plate H and comes in contact with the lower portion of said end g^4 . With the outer vibrating end portion of the hinged plate H is connected pivotally one end of separate folding links h' h' , the other ends of which links are pivotally connected with the respective bars g^8 on the inner side of the hopper G .

Upon the top of the baling-chamber B , at a point nearly equidistant from its opposite ends, is a standard I of suitable height. Upon the upper end of standard I and rear side portion is an upwardly-extended bracket or plate i , upon each side of which plate is an inclined thimble i' . In each thimble is inserted the screw-threaded upper end of a rod i^2 , upon which are the securing-bolts i^3 i^3 . The lower end of each rod is extended to the rear end portion of the baling-chamber B and extended through a thimble i^4 on the side of the said chamber, said end of said rod being screw-threaded and secured to the thimble by securing-nuts i^5 . Upon the rear side portion of plate i is a bracket i^6 , in which bracket is journaled a sheave i^7 . In the plate i opposite the sheave i^7 is an opening i^8 , and in the upper end of said plate between the thimbles i' is an opening i^9 . Upon the top of the baling-chamber B , a short distance from the standard I in the direction of the hopper G , is a square rock-bar k , which is arranged in a transverse direction to the said baling-chamber and each end turned and

journaled at each end in pillow or journal boxes k' k' on said baling-chamber.

To one side of the bar k is secured by the yoke k^2 the lower end portion of the vibrating arm K , the ends of said yoke being screw-threaded and extended through said bar and provided with securing-nuts k^3 . Upon the upper end of the arm or bar K and upon the side of said bar toward the hopper G is the material-feeding devices M , which consist, first, of a block m , considerably less in width than that described between the sides of the feed-receptacle A , and about one-third the described length of the feed-receptacle A . In the upper side portion of the block m is a longitudinal groove m' , in which is fitted the upper end portion of the arm or bar K , said bar being secured in position by cross-strips m^2 , extending across the slot m' and secured by bolts m^3 to the block m , upon which bolts are nuts m^4 .

Upon the under side portion of the block m is a hollow case for forcing the loose material into the feed-receptacle A , which is of the same length as block m and about one-half the width of said block and extends downwardly a considerable distance, so as to force the loose material out of the hopper G . The case consists of the sides m^5 m^5 , ends m^6 m^6 , and bottom m^7 , the said bottom m^7 being inclined rearwardly at an angle to the sides, as seen in Fig. 2, and secured to the block m by the screw-threaded rods m^8 m^8 , upon the ends of which rods, on the under side of bottom m^7 , are nuts m^9 . The upper ends of the rods m^8 extend through the block m and are provided with nuts m^{10} . Instead of the precise form of case as described I may employ a solid block of material, as the occasion demands.

In order to increase the weight of the feeder M , separate removable plates N are placed in position upon block m , on each side of the block m' and extending longitudinally with said block. Said plate N is perforated and through which perforations the extended ends of the rods m^8 m^8 are passed, the nuts m^9 being employed to secure the plates upon block m . Other plates are added to block m as additional weight is required. On each side of the feeding-case and hinged to the block m by hinges o o is a wing O of the length as the said case. On the outer side of one wing between the hinges o o is connected rigidly one end of a bar o^2 , the other end of which bar extends upwardly a short distance above the top portion of the block and the plate N and is bent outwardly from said wing a short distance. Upon the outer side portion of the other wing O is a bar o^2 , which is the same as upon the first wing mentioned. With the outer end portion of one bar o^2 is connected one end of a spiral spring o^3 , the other end of which spring is connected with the outer end portion of the other bar o^2 . Said bars o^2 o^2 act as levers to throw the wings outwardly from the sides of the feeding-case and in con-

nection with the said spring to hold the said wings normally in an outwardly-extended position.

With the side of the vibrating arm K, in rear of the feeder M, is pivotally connected one end of a rod P, the other end of which rod is extended through the opening i^9 in the plate i on standard I and is of such a length as to permit the full descent of the said feeder M and is also provided with a fixed button p . Upon rod P, between the end connected with bar K and the plate i , is a spiral spring p' of sufficient length to relieve the shock in upward movement of the bar K. Upon rod P and connected with the button p is a spiral spring p^2 , which extends nearly the same length as spring p' and relieves the shock on the downward movement of the feeder.

On one side of the feed-receptacle A and at the extreme forward end is a casting R, which extends beyond the said end of the said receptacle, and upon the upper side of the casting is journaled in a horizontal position a small pulley r on the same side of the press and upon the side of the baling-chamber and in rear of standard I, and directly beneath the pulley i^7 is a vertical pulley r^2 .

On the bar K is an antifriction-roller s , with the journal of which is connected the ends of a U-shaped guide S. With guides S is connected one end of a rope T, the other end of which rope is extended over the sheave i^7 , thence over pulley r^2 on the baling-chamber B, thence over the pulley r on the feed-receptacle and the other end extended through the forward end of the pitman F, near the head-block E, and secured thereto.

V represents the division-board for dividing the bales, showing the openings for the baling-wires.

In operation the material to be baled is placed loosely within the hopper G. As soon as the hopper G is filled power is applied to the pitman F and head-block E to move the head-block in the direction of the baling-chamber B to a position seen in full lines in Figs. 1 and 2, in which movement the folding plate H turns upon the hinge e and takes a horizontal position, the angle-plate h comes into contact with the lower portion of the end g^4 of the hopper, and said end is moved forward in the vertical position, as seen in Figs. 1 and 2, compressing the loose material in the hopper G between said movable compressing-plate and the end g^3 of the said hopper within a small compass. In the movement of the head-block E to a position at the entrance of the baling-chamber, as in full lines in Fig. 2, the feeder M is drawn upward by the rope T, the shock to the bar K I being relieved by the spring p' on the rod P. In the upward movement of the bar K the antifriction-roller s moves over the forward edge of said bar, obtaining an increased purchase as it approaches the feeder M. Upon the withdrawal of the head-block E from the baling-chamber B the slack in the rope T permits the feeder M to

descend, the rapidity of the movement being first assisted by the spring p' , which exerts a forward movement on the bar K, and as soon as the bar becomes slightly inclined in position the weight of the feeder causes the compressor to descend with violence, the bar K entering slot g^8 in the end g^3 of the hopper, and the compressed material within the hopper is forced within the feed-receptacle and into the position as seen in dotted lines, Fig. 2, the wings O O striking the inner portion of the inclosed sides $g g$ and are drawn in the direction of the sides m^5 of the compressing-case as they approach the sides of the feed-receptacle, and thus carrying with the feeder all the material into the feed-receptacle, especially the loose ends, which extend to the sides of the feed-receptacle, the shock in the descent of the feeder being borne by the spring p^2 on the rod P, which rod moves through the opening in the plate i . In the descent of the feeder M the movable compressing end g^4 of hopper G is forced to the forward end of the hopper by the expansion of the material and in the inclined position, as seen in Fig. 2, and thus affording an opportunity to fill the hopper in the interval between the movement of the head-block toward the baling-chamber and the withdrawal of the feeder M from the feed-receptacle by the power communicated to the rope T in said movement. In reciprocating the head-block and pitman rapidly the full benefit is obtained of the power operating the pitman, the charges of the compressed material in the feed-receptacle affording sufficient expansion to effect a rebound of the head-block at each compression.

In ordinary baling-presses employing a hopper difficulty occurs in dropping the division-board within the feed-receptacle, the liability being that the division-board will either turn upon its side or in falling directly change its position at an angle to the sides of the feed-receptacle. To obviate this, the division-board V is placed between the guide-bars g^9 g^9 , on the outer side of the movable end g^4 of the hopper G at the moment the said end has moved forward to compress the material in the hopper G, the lower end of said division-board resting upon the step g^{10} and held against a fulcrum formed by the block g^{12} , as seen in dotted lines in Fig. 2. Upon forcing backward with the hand the upper end of the division-board the lower end is disengaged from the step g^{10} , and the division-board falls within the feed-receptacle, guided by the guide-bars g^9 .

My invention accomplishes the operation of compressing the loose material in the hopper and does away with the service of an extra hand in running the press.

Having fully described my invention, what I now claim as new, and desire to secure by Letters Patent, is—

1. In a feeder for baling-presses a weighted material-feeding body, and wings hinged to said body.

2. In a feeder for baling-presses a weighted material-feeding body, and spring-controlled hinged wings to said body.
3. In a feeder for baling-presses the combination with a material-feeding body, of wings upon the opposite sides of said body hinged thereto, and operation-bars connected with each wing and a spring connection for the separate bars.
10. 4. In a feeder for baling-presses, the combination with a weighted material-feeding body, of a wing on opposite sides of said compressing-body and hinged thereto, a bar connected with each wing upon the outer side 15 portion and bent outwardly from and at an angle to said wing, and a spiral spring connected with the outer end of each bar.
5. In a baling-press, the combination with the feed-receptacle for the reception of the material to be baled, of a hopper having inclined sides, a weighted material-feeding body adapted to enter said hopper, and material-gathering hinged wings upon said weighted feeding-body.
25. 6. In a baling-press, the combination with the feed-receptacle for the reception of the material to be baled, of a hopper having inclined sides and ends, and a vertical slot in one of said ends, a weighted material-feeding 30 body adapted to enter said hopper, and a bar for actuating said weighted body, adapted to enter the slot in said hopper, and spring-actuated hinged sides to said weighted feeding-body.
35. 7. In a baling-press the combination with the feed-receptacle for the reception of the material to be baled of a baling-chamber, a head-block and a pitman a vibrating bar pivotally connected at one end with the baling- 40 chamber, and a weighted body adapted to enter the said feed-receptacle upon the other or vibrating end of said bar, a standard upon said baling-chamber in rear of said vibrating bar, and a bracket upon said standard having an opening and a guide-rod extending 45 through said opening and pivotally connected with said vibrating bar, and springs upon said rod upon opposite sides of said bracket, adapted to receive the recoil of said weighted body, a pulley upon said bracket, and pulleys upon 50 said baling-chamber and the forward end of said feed-receptacle, an antifriction traveling yoke upon said vibrating bar, and a rope connected at one end with said yoke and extending over the pulley upon said standard 55 and also over the pulleys on said baling-chamber and feed-receptacle, and connected at the other end with the said pitman.
8. In a baling-press, the combination with the feed-receptacle and with the hopper upon 60 said receptacle having a movable end, and a passage between the said hopper and the outer side of the said receptacle, of vibrating bars connected with said movable end of said hopper pivotally connected with said feed-receptacle, and spring-plates upon the outer side 65 of said feed-receptacle adapted to hold said vibrating bars in an upright position.
9. In a baling-press, the combination with the feed-receptacle and with the hopper upon 70 said receptacle having a movable end of a step upon the outer side portion of said movable end, adapted to support the division-board, a fulcrum upon said movable end above said step, and guide-bars upon said movable 75 end for the said division-board.
